UNITED STATES PATENT OFFICE.

MICHEL GOBERT, OF NEW YORK, N. Y.

ATTACHMENT FOR CIGARETTE HOLDERS.

Application filed June 22, 1922. Serial No. 570,237.

This invention is an attachment for cigarette holders and the object of the invention is to provide simple, economical and efficient means for not only facilitating the removal 5 of short unburnt ends of cigarettes from a holder, but to also keep the smoke passage of the holder from becoming clogged.

Various attachments for use in conjunction with cigarette holders have been suggested, the function of which has been, uniformly, to eject the unsmoked butt.

The present invention constitutes a simple, economical and efficient construction for readily accomplishing this result in a more economical and efficient manner and in addition thereto precludes clogging of the holder.

In one of its preferred practical forms, the invention is constructed from wire formed into one or more rings adapted to embrace the end of the holder adjacent the cigarette pocket and to firmly grip said holder for the purpose of maintaining the device in position. This portion of the device may be constructed to compensate for cigarette holders of different sizes and may readily adjust itself as conditions may require. From this ring portion of the device, a wire is bent so as to extend over the 20 end of the holder and into the cigarette pocket at the base of which pocket the wire is off-set to form a shoulder on which the end of the cigarette is adapted to seat when thrust into the pocket. The wire is continued beyond the off-set or shoulder to such extent as to project through the smoke passage of the holder to substantially the end thereof normally held between the lips.

When the device is in position on the holder, the cigarette may be smoked in the usual manner until it is practically all consumed, whereupon the device may be withdrawn from the holder, the cigarette shook and turned out of the device and the device 45 thereupon returned to the holder. The removal and replacement of that portion of the device which extends through the smoke passage will serve to keep the passage clear and remove any obstructions that may have 50 become lodged therein, so that when a new cigarette is inserted in the holder, it may be smoked in a free and unrestricted manner.

The device of this invention is light and does not unduly encumber the holder. Moreover, when made of wire as described

its cost is negligible. It is to be understood however that it may be constructed from metal other than wire without departing from this invention as will be apparent from the following detailed description.

Features of the invention, other than those specified, will be apparent from the following description and claim, when read in conjunction with the accompanying drawings.

The accompanying drawings illustrate different practical embodiments of the invention, but the constructions therein shown are to be understood as illustrative, only, and not as defining the limits of the invention.

Figure 1 is a side elevation of the preferred form of the invention showing the same associated with a cigarette holder, a portion of which is illustrated in central section.

Figure 1^a is a section on the line 1^a—1^a of Figure 1, and

Figures 2, 3 and 4 are perspective views illustrating modified forms of the invention.

Referring to the drawings and, more particularly, to the construction shown in Figure 1, the attachment is illustrated as constructed from wire bent to form a ring 1. The ring is made considerably larger than the diameter of the largest cigarette holder with which it is adapted to cooperate and is crimped or corrugated so that it will appear as shown in Figure 1. By virtue of this formation it may be readily expanded or contracted to tightly embrace the end of a cigarette holder and firmly grip the same. If desired, the ring 1 may be made of springy or resilient material having a normally contracted form, whereby it is adapted to be sprung over a cigarette holder and, by its own elasticity, tightly grip the holder.

The wire from which the ring is formed is bent so as to extend from one side of the ring upwardly and over the end of the cigarette holder 2 as shown at 3 and thence downwardly into the cigarette receiving pocket 4 of the holder as shown at 5. The part 5 extends substantially to the base of the pocket 4 where it is offset as shown at 6 to form a shoulder against which the end of a cigarette is adapted to abut when a cigarette is forced into the pocket in the usual manner. Beyond the offset or shoulder 6

the wire extends in a substantially straight line as shown at 7 through the smoke passage 8 of the holder to substantially the end of the mouth piece. In practice, the wire forming the device is preferably quite light so as not to unduly encumber the holder and so that the part 7, which extends through the smoke passage, will not completely fill the passage but will enable proper draft. In order that the cigarette may fit tightly into the pocket 4 the portion 5 of the wire is preferably flattened as shown in Figure 1^a and this construction will prevent leakage of air about the cigarette. If desired, the entire length of the wire from which the device is formed may be flattened as shown in Figure 1^a so as to more closely conform to the shape of the holder. I have found that when the wire is made of silver, gold or other precious metal the device, instead of encumbering or detracting from the appearance of the holder will serve as an ornamentation thereto.

The attachment described can be readily associated with a cigarette holder after the manner shown in Figure 1 and when in place in no wise interferes with the introduction of a cigarette in the usual manner. However, after the cigarette has been smoked and it is desired to remove the butt the device may be withdrawn from the holder during which operation the shoulder or offset 6 will force the butt out of the pocket 4. As soon as the device is removed and inverted, the butt will fall out of engagement therewith, whereupon the attachment may be replaced on the holder to condition the holder to receive another cigarette. During the operation of removing the butt and subsequent replacement of the device, the part 7 of the stem will traverse the smoke passage 8 and clear it of any obstruction which may have lodged therein. The parts 3, 5 and 7 may be said to constitute the stem referred to and it will thus appear that, generally speaking, the device as shown in Figure 1 embodies means for encircling and gripping a cigarette holder and having associated therewith a stem extending through the cigarette pocket and smoke passage of the holder to preclude clogging of the smoke passage and provided with an offset or shoulder on which the cigarette is adapted to seat.

If desired, the device may be modified in construction in various ways such, for example, as shown in Figure 2, wherein the ring 1^a, which corresponds to the ring 1, is not crimped but is adapted to fit over the outside of a holder adjacent the end thereof. In constructing the holder of Figure 2 I may provide the ring 1^a with integral depending arms 9 formed integral with the ring and adapted to resiliently engage with the outside of the holder after the manner

of clamping jaws to hold the ring 1^a firmly in position. Although it is not necessary, finger pieces in the form of ears 10 may be associated with the ring 1^a or, in practice, such finger pieces may be associated with the construction of the ring of Figure 1. I have, however, found in practice that the ring may be readily grasped without the aid of such finger pieces.

The structure of Figure 2 embodies a stem 75 offset at 6^a and functioning in the same manner as the stem of Figure 1.

In Figure 3, there is illustrated a further modified form of construction embodying two rings 1^b and 1^c formed by bending up a wire as shown and provided with a depending stem 6^b. In the construction of Figure 3 the ring 1^b may be made to abut the end of the holder while the ring 1^c embraces the holder or, if desired, both may be in proportion to embrace the holder.

In Figure 4 I have illustrated another modified form of the invention which, instead of being constructed from wire, is made of sheet metal. The ring 1^d which is adapted to embrace the holder is split to form a pair of resilient fingers adapted to tightly clamp around the holder, while the stem is stamped up integral with the ring and the portion 7^d which extends through the smoke passage of the holder is reduced in width so as not to unduly fill said smoke passage. The structure shown in Figure 4 may, if desired, be made from wire by bending the wire so as to form loops constituting spring 100 fingers which embrace and grip the holder.

In practice, I preferably employ either the form of Figures 1 or 4 as the adaptability of these forms to fit holders of different sizes is of pronounced advantage. In all of 105 the forms described, however, the offset stem is held in place by means embracing the holder and the stem is sufficiently long to extend through the smoke passage. I have found in use that nicotine, dust and other 110 impurities collect on this portion of the stem and when the attachment is removed from the holder such impurities may be readily removed from the stem so that when the attachment is readjusted on the holder the 115 holder will be clean and fresh.

In the foregoing detailed description I have set forth different embodiments of the invention for the purpose of illustrating a few of the many ways in which the invention may be made and have also specifically referred to the use of the device in connection with cigarette holders. I am aware, however, that by slight modification in shape and size the structure may be well adapted 120 to be used in conjunction with cigar holders. For these reasons the invention is not restricted to the specific showing of the drawings but is to be understood as broadly novel 125 as is commensurate with the appended claim. 130

Having thus fully described the invention, what I claim as new and desire to secure by Letters Patent, is:

An attachment for cigarette and cigar holders embodying a stem adapted to loosely extend through the smoke passage and cigarette or cigar receiving pocket of a holder, an offset intermediate its ends to form a shoulder on which a cigar or cigarette, inserted into the holder, is adapted to seat so

that said cigar or cigarette will be forced out of the pocket when the attachment is removed from the holder, said stem being bent to embrace the edge of the pocket of the holder to maintain the attachment in 15 position independently of the stem.

In testimony whereof I have signed the foregoing specification.

MICHEL GOBERT.
